CLAIM

The ornamental design for a face slimming strap, as shown and described.

DESCRIPTION

FIG. 1 is a front perspective view of a face slimming strap showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 2; and, FIG. 10 is a perspective view thereof, where the face slimming strap is in a folded state.

The dash-dash broken lines in the drawings depict portions of the face slimming strap that form no part of the claimed design. Additional dash-dash broken lines shown in FIG. 10 depict an environmental subject matter and form no part of the claimed design. The dot-dash broken lines shown in FIGS. 2 and 9 represent boundaries of the enlarged portion that form no part of the claimed design.
